US00D931217S

(12) **United States Design Patent** (10) **Patent No.:** **US D931,217 S**
(45) **Date of Patent:** ** *Sep. 21, 2021

(54) **POWER PLUG**

(71) Applicant: **Sonos, Inc.**, Santa Barbara, CA (US)

(72) Inventors: **Mieko Kusano**, Santa Barbara, CA (US); **Roland Bird**, Eindhoven (NL); **Niels van Hoof**, Eindhoven (NL); **Lukasz Natkaniec**, Munich (DE); **Wilfred Wei**, Shanghai (CN)

(73) Assignee: **Sonos, Inc.**, Santa Barbara, CA (US)

(*) Notice: This patent is subject to a terminal disclaimer.

(**) Term: **15 Years**

(21) Appl. No.: **29/681,769**

(22) Filed: **Feb. 27, 2019**

Related U.S. Application Data

(63) Continuation of application No. 29/611,086, filed on Jul. 18, 2017, now Pat. No. Des. 843,942, which is a continuation of application No. 29/523,318, filed on Apr. 8, 2015, now Pat. No. Des. 796,447.

(57) **CLAIM**

The ornamental design for a power plug, as shown and described.

DESCRIPTION

FIG. 1 is a perspective view of a power plug showing the new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The dash-dash broken lines represent the portions of the power plug that form no part of the claimed design. The dot-dash broken lines define the bounds of the claimed design and form no part thereof.

1 Claim, 3 Drawing Sheets
